UNITED STATES PATENT OFFICE

1,942,026

SPIRALLY-BOUND SHEAF

Samuel Groener, Paris, France, assignor to
Frank Amato, New York, N. Y.

Application June 6, 1933. Serial No. 674,492

3 Claims. (Cl. 281—25)

My present invention relates generally to the employment of a helical binding element for maintaining sheaves or stacks of paper or the like in associated relation and against accidental separation.

My invention in one of its aspects is an improvement on the arrangement shown in United States Letters Patent 1,516,932 issued on November 12, 1924. This patent shows a helical binding element threaded through a group of equidistantly spaced openings in a stack of sheets for maintaining said sheets in associated relation. It, however, has no provision for limiting the relative movement between the stack and the spiral binding element and therefore for preventing accidental disassociation of the two.

The general object of my invention is the provision of means for preventing the accidental disassociation of an element of a stack from its position therein or of the stack as an entirety from its relation to the helical binding element.

It is a further object of the invention that the means as hereinabove referred to for preventing disassociation shall be so devised and related as 25 to interfere to the minimum degree with the free manipulation of the sheets with reference to each other and with reference to the spiral binding member.

For the attainment of these objects and such 30 other objects as will hereinafter appear or be pointed out, I have illustrated several forms of my invention in the drawing, wherein:

Figure 1 discloses one embodiment of my invention in its relation to a stack of sheets of 35 paper in book form;

Figure 2 is an enlarged detail view of the binding element of Figure 1 with the middle portion omitted;

Figure 3 is a detail view of a portion of the binding element, similar to Figure 2, except that it is 40 taken at right angles thereto as indicated by the line 3—3 and the arrows;

Figure 4 is an end view of the binding element of Figure 1; and

Figure 5 and 6 show respectively a side view and an end view of a portion of a modified form of the binding element.

As disclosed in the aforementioned U. S. Letters Patent, it is found that the spiral binding element will tend to work loose from the stack, particularly where there is substantial friction between the stack and the binding element as where the coils of the binding element are of small diameter in relation to the height of the stack of sheets 55 they unite, or where the pitch of the helical coils

is not exactly in proportion to the spacing of the holes in the sheets and a further cause is the catching of the terminal portions of the binding element, either on the surface of the paper or within the holes thereof. All of these causes, as 60 has been mentioned, tend to work loose the binding element, necessitating constant adjustment of the spring to bring it back into its normal position, and also result in injury to the leaves of the book because of the tearing effect on the paper 65 of the ends of the binding element.

My invention, therefore, contemplates the provision of means for avoiding undesirable displacement of the binding element thereby avoiding inconvenience and damage, without, in any way, interfering with the use of the book.

Referring to the drawing in detail, I show at 11 a stack of paper sheets, which are, by way of example, shown as all of the same size and of rectangular form, although they need not necessarily 75 be so. The stack of sheets has a row of holes 13 which are shown as equidistantly spaced and which are intended to accommodate the coils of a helical element 15 by a threading operation. I have found it convenient to use a spiral spring 80 for this purpose, although other materials not necessarily elastic or flexible will answer my purpose, provided they offer the proper rigidity. At 17, I show the terminals of the element 15 bent at an angle to the direction of the coils, and as 85 clearly shown in Figure 2, these terminal portions are bent underneath the adjacent coil which serves to support them in position against certain displacing forces so as to position them substantially within the surface of the cylinder containing the coils of the spiral spring. This abrupt interruption in the helical course of the coils will prevent retraction of the coils from the holes without, however, preventing any substantial obstacle to the free angular displacement of sheets for 90 substantially 360°. In this manner also the terminals 17 are protected by their contact with the adjacent coils of the spring 15 against displacement, and they are also located so that the backs of the individual leaves cannot come in contact 95 therewith and be torn, as might be the case if the terminals projected into the interior of the spring.

I have found the construction just described very convenient in the relation described. Other forms may be found convenient for other purposes. For instance, in Figures 5, and 6, I show a coil spring 15' with its ends deformed from their helical course and located in a plane indicated at P, whereas the normal helical formation is indicated at S. In other words, the terminal 110

portions are portions of a coil, the plane of which is transverse to the longitudinal extent of the binding element.

With this construction the obstruction which prevents removal is not as positive in action as in the preceding form, but before the binding element can move out of its normal position to a substantial extent, its terminal portion or portions must be deformed back into the helical contour, and this is resisted by the element in proportion to the rigidity of the material of which it is constituted.

Having thus described my invention and illustrated its use, what I claim as new and desire to secure by Letters Patent is:

1. In combination with a stack of superimposed paper sheets or the like, having adjacent one edge thereof a series of substantially evenly spaced perforations, a helical element engaging said perforations so as to flexibly unite the sheets, the terminal portions of said element being bent from their helical conformation through substantially a right angle, and being of a length so that they

extend beneath the next adjacent coil, whereby said terminal portions are disposed substantially longitudinally of said helical element and within an imaginary cylindrical surface containing said helix, and whereby said terminal portions are adapted to prevent disassociation of said helical element from the perforations, without destroying the flexibility of the connection.

2. A binding element for associating sheets of paper or the like in book form comprising a series of spaced coils in end to end relation and a terminal portion of an end coil bent at substantially a right angle to the course of the coil and into adjacency with the inside portion of the next adjacent coil.

3. A binding element for associating sheets of paper or the like in book form comprising a series of spaced coils in end to end relation and each of the terminal portions of the end coils being bent into the general direction of the axis of the coil and into adjacency with the inside portion of the next adjacent coil.

SAMUEL GROENER.
